PUNCHING DIE SET

John H. Bennett, Bridgeport, Conn., assignor to Minnie
Punch & Die Company, Inc., Union Township, N.J.,
a corporation of New Jersey

Filed Nov. 1, 1961, Ser. No. 149,379
7 Claims. (Cl. 83—623)

The present invention relates to a die set for punching perforations in sheet material and more particularly to such a set which is preferably employed to produce small quantities, i.e. up to about 25,000 perforated pieces, from thin material which may be up to and including $\frac{1}{8}$ of an inch thick mild sheet steel.

The manufacture of small quantities of perforated pieces, generally referred to as "short-run" quantities, has heretofore been expensive and time consuming because of a number of factors. Thus while pieces may be made by individually punching or drilling each perforation in each piece one at a time, naturally since each piece must be handled as many times as it has perforations, such a procedure becomes increasingly expensive with each perforation required. To form all the perforations at once, as by making a die set, is also expensive particularly for just short-run quantities as the dies are approximately as expensive to manufacture as "long-run" dies made by tool and die makers. Moreover, adjustable punch and die sets, while heretofore proposed for short-runs, have not been found completely satisfactory because of their initial expense, their loss of accuracy during use, the cost of making a template, limitations as to closeness of perforations, etc.

It is accordingly an object of the present invention to provide a die set that obviates the above disadvantages for perforating short-run quantities of pieces.

Another object of the present invention is to provide a short-run punching die set which is economical to fabricate and may be made by semi-skilled labor with a minimum amount of operations instead of requiring tool and die makers.

A further object of the present invention is to provide a die set of the above-noted type which is reliable and accurate in operation and which may be easily and simply maintained in working order.

An additional object of the present invention is to provide a punching die set which may be quickly and easily secured to a press requiring little, if any, change in the bed and ram plates of the press and which may be easily removed therefrom.

In carrying out the present invention, a feature resides in the forming of the die set by the use of a punch plate and a die plate. The two plates are secured together in parallel relation for movement relative toward and away from each other. The punch plate has secured thereto the punches while the die plate is provided with die members that cooperate with the punches to punch the perforations in the piece. By securing the die set to the ram of a punch press, the movement of the ram towards the steel pad causes compression of the punch plate and die plate to thereby punch the perforations in the piece positioned therebetween.

According to the present invention the punches and the die members are formed of a material that is referred to as "prehardened" though relatively easily machinable and has an approximate Rockwell hardness of C-44. The punch and die plates are formed of a softer material such as aluminum. The die number and the punches are each formed to have a head with an undercut or smaller collar. With this structure the punches and the die numbers are easily secured to their respective plates simply by exerting a compressive force thereon that forces each head into the plate and the material displaced by the head is forced into

2

the undercut collar of the punches and die members to thereby securely fasten the punches and die members in their respective plates.

Other features and advantages will hereinafter appear.

In the drawing:

FIGURE 1 is an elevation of the die set of the present invention shown secured to the ram plate of a punch press.

FIG. 2 is a view taken along the line 2—2 thereof.

FIG. 3 is a section taken on the line 3—3 of FIG. 1.

FIG. 4 is a detail showing a step in the fabrication of the die set of the present invention.

FIG. 5 is a section of a punch prior to it being secured in the punch plate.

FIG. 6 is a section of the punch of FIG. 5 secured in the punch plate.

FIG. 7 is a section of a die member secured in the die plate.

FIG. 8 is a plan of a die.

FIG. 9 is a plan of another die.

Referring to the drawing, the die set of the present invention is generally indicated by the reference numeral 10 and includes a punch plate 11 and a die plate 12 that are substantially coextensive. The two plates 11 and 12 are parallel and mounted for movement towards and away from each other by guide pins 13 secured to the punch plate and operating in guide bushings 14 secured to the die plate. A spring 15 encircles each of the guide pins and urges the two plates apart while retaining means, such as C-ring 16, snap into a circular groove 17 formed in each of the guide pins to prevent separation of the plates.

The die set 10, as shown in FIG. 1, is secured to a ram plate 18 of a punch press having a stationary steel pad 19. Screws 20 pass through apertures 21 formed at opposite corners of the punch plate and are threaded into threaded apertures 22 formed in the ram plate to thereby securely hold the die set 10 to the ram plate for movement therewith. Holes 23 formed in the die plate 12 accommodate the head of the screws 20 when the plates are moved together and enable the die set to be secured to the ram plate without disassembling the set. Moreover, it will be clear that the steel pad 19 is formed to have apertures 24 that accommodate the ends of the guide pins during the punching operation.

In the specific embodiment of the invention shown, the die set includes a plurality of punches 25 secured to the punch plate 11 and a plurality of die members or dies 26 secured in the die plate 12, there being one die for each punch. The specific embodiment of the die set of the present invention is designed to punch three circular holes of approximately the same size in a slightly triangular pattern. It will be appreciated that any desired size of perforations and relative position may be punched in a piece by simply using the required size punches and die members secured in their respective plates at the proper location. Moreover, for perforating a different size of piece a different size of the plates 11 and 12 may be used than the size herein described.

In carrying out the present invention, FIG. 6, each of the punches 25 is secured to the punch plate by the punch having a portion 27 of the punch plate displaced into an undercut collar 28 of the punch 25. The collar 28 is located between a head 29 and a stem 30 with the punching portion 31 extending therebeyond. The diameter of the stem portion 30 is somewhat smaller than the head portion 29 and yet is larger than the undercut collar 28. It will be appreciated that the punch 25 is accordingly held securely in the punch plate 11 and also that the head of the punch is flush with the surface of the punch plate.

In fabricating the die set of the present invention, an aperture 32 (FIG. 5) is initially formed in the punch plate 11 in the location where it is desired to have a

perforation formed in a piece (not shown). The size of the aperture 32 is approximately that of the stem 30 and a punch 25 is placed in the aperture 32. After an aperture 32 has been formed for each perforation to be made in the piece and a punch 25 of the correct size positioned therein, the punches are pressed into the die plate to force the material 33 of the punch plate under the head 29 of the punch 25 into the undercut collar 28 to thus form the holding portion 27. It is contemplated to force all the punches into the punch plate in one pressing operation.

After the securing of the punches 25 within the punch plate, the die plate is then aligned therewith by the guide pins and a mark is made in the die plate, as shown in FIG. 4, by a central projection 34 on each of the punches. The die plate 12 is then removed and an aperture 35 (FIG. 7) formed therein to receive a die 26. The die has a construction similar to that of the punch in that it has a head 36, an undercut collar 37 and a stem 38 with the stem 38 having a diameter substantially the same as the hole 35 but yet larger than the undercut collar 37 and smaller than the head 36 so that a holding portion 39 of the die plate is circumferentially forced into the undercut collar to secure the die in the die plate. The diameter of a through aperture 40 of each die is substantially that of the punching portion 31 of the punch 25 cooperating with each die.

It is presently preferred to also secure the guide pins 13 and guide bushings 14 in a similar manner such that they can also be secured by a simple pressing operation. Thus they would each include a head, an undercut collar and a stem.

To complete the die there is additionally provided at selected positions locating guide pins 41 secured in the die plate 12, locating pin holes 42 formed in the punch plate 11 and a resilient stripping member 43.

In the present invention, the punch plate and the die plate are formed of a material softer than the material forming the punches 25 and die members 26 and is preferably aluminum, both of which may be of the same thickness. However, in the embodiment herein disclosed, the die plate is shown about twice the thickness of the punch plate, the latter being for example approximately $\frac{1}{8}$ of an inch thick. The material from which the punches and the die members are made is harder than the plates 11 and 12 so that the plates distort when the punches and die members are forced therein rather than the latter distorting. The material may be a prehardened high strength steel capable of being easily machined (as by an automatic screw machine) requiring no further heat treatment. It is presently desired that the guide pins and the guide bushings also be formed of this material.

While each of the punches 25 have been shown approximately the same, it will be clear that the punches and die members are made to have a diameter of the punching portion 31 which would form a perforation of the desired size in the piece. Moreover, it is also clear that the location of the punches will also be determined by the perforations to be formed in the piece.

Shown in FIG. 8 is a cluster die 44 which may be employed according to the present invention for forming a plurality of small, closely spaced perforations in the piece rather than having independent die members for each perforation. Additionally if any other than a round perforation is to be formed in the piece, the die and punch may be easily machined to have the shape of the desired perforation such as the square aperture 45 shown in a shaped die 46 of FIG. 9.

It will accordingly be appreciated that in all forms of the invention herein disclosed that both the punches and the die members whether of single perforation forming or cluster forming, or shaped are provided with an undercut collar located between a head and a stem with

each punch and die being secured by pressing the head into the plate to distort material into the undercut collar.

In use, with the die set fastened to the ram plate of the press and a piece positioned in the die set by the operator at a predetermined locality determined by the locating pins, the ram plate 18 is brought towards the steel pad 19 forcing the punches 25 into the die members 26 to thereby shear the perforations in the piece. When the ram plate 18 is retracted to the position shown in FIG. 1, the stripping member 43 will free the piece from the punches 25 permitting removal thereof while the slugs formed by the punches will rest on the steel pad 19 and may be easily removed by an air blast.

It will be appreciated that the surface of the punch plate 11 that engages the ram plate 18 is flat with the heads 29 of the punches being substantially flush with this surface while the bottom surface of the die plate except for the ends of the guide pins is also flat thereby providing even pressure distribution throughout the two plates. Moreover, if after some usage it has been found that the cutting edges of the punches and the die members are becoming dull they may be effectively sharpened by removal of the C-ring 16, separating of the plates and a grinding of the top surface of the die members and of the cutting surface of the punches. The top surface of the head of each die member is substantially flush with the top surface of the die plate to facilitate the sharpening and also the positioning of the piece.

From the foregoing it will be appreciated that there has been disclosed a die set which is economical to fabricate and which is effective to produce short-run quantities of perforated pieces. One feature which enables achievement of these advantages is the provision of forming each of the punches and die members to have an undercut collar into which portions of their respective punch and die plates are forced to thereby securely maintain these pieces in position. The plates are quickly and economically prepared to receive the punches and die member by merely forming holes therein, as by punching or drilling, at the localities wherein it is desired to form perforations in the piece.

Variations and modifications may be made within the scope of the claims and portions of the improvements may be used without others.

I claim:

1. A punching die set for forming perforations in relatively thin material comprising a substantially flat punch plate, a substantially flat die plate, means mounting the punch plate and die plate in parallel for movement toward and away from each other, this mounting means including guide pins at diagonal corners of the punch and die plates for alignment of the two plates, at least one aperture formed in the punch plate, a punch mounted in the aperture of the punch plate, said punch including a head, an undercut collar and a stem with the stem having a cross-section approximately that of the aperture and being larger than the collar but smaller than the head, the punch being secured in the punch plate by the head being forced into the punch plate to displace material of the punch plate around and into the undercut collar, said die plate being formed of relatively soft material and said punch being formed of relatively hard prehardened machineable steel alloy material.

2. A punching die set for forming perforations in relatively thin material comprising a substantially flat punch plate, a substantially flat die plate, means mounting the punch plate and die plate in parallel for movement toward and away from each other, the mounting means including guide pins at diagonal corners of the punch and die plates for alignment of the two plates, at least one punch mounted in the punch plate, at least one die mounted in the die plate for cooperation with the punch, the punch and die each including a head, an undercut collar and a stem with the stem being of larger cross-section than the collar but smaller than the head,

the punch and die being formed of prehardened machineable steel alloy and being secured in their respective plates by a portion of their respective plates being around and in the undercut collar.

3. The invention as defined in claim 2 in which the head of the die and the head of the punch are recessed into their respective plates to be at least flush therewith.

4. The invention as defined in claim 2 in which the means for mounting includes a guide pin and a guide bushing with one being secured in one plate and the other being secured in the other plate, said guide pin and said guide bushing each having a head, an undercut collar and a stem with the stem being larger in cross-section than the collar but smaller than the head, said guide pin and said guide bushing being secured in their respective plates by a portion of their respective plates being forced in and around the undercut collar.

5. A punching die set for forming perforations in relatively thin material comprising a substantially flat punch plate, a substantially flat die plate, said plates being formed of relatively soft metal, means mounting the punch plate and die plate in parallel for movement toward and away from each other, the mounting means including guide pins at diagonal corners of the punch and die plates for alignment of the two plates, at least one punch mounted in the punch plate, at least one die mounted in the die plate for cooperation with the punch, the punch and die each including a head, an undercut collar and a stem with the stem being larger in cross-section than the collar but smaller than the head, the punch and die being secured in their respective plates by each head being forced into the plate to displace a portion of their respective plates around and into the undercut

collar, said punch and die being made of a relatively hard prehardened machineable steel alloy metal.

6. The invention as defined in claim 5 in which the plate material is aluminum.

5 7. A punch for use in a punching die set for forming perforations in relatively thin material comprising a head, a stem and an undercut collar positioned between the head and the stem, the cross-sectional periphery of the stem being larger than that of the undercut collar but being smaller than that of the head, the stem including a punching portion, said punch being formed in one piece from a prehardened, machinable steel alloy.
